ANTHELMINTIC DISTILBAZOLES AND METHOD
 Arthur P. Phillips, Tuckahoe, and Robert B. Burrows,
 Ardsley, N.Y., assignors to Burroughs Wellcome & Co.
 (U.S.A.) Inc., Tuckahoe, N.Y., a corporation of New
 York
 No Drawing. Filed June 7, 1961, Ser. No. 115,996
 7 Claims. (Cl. 260—240.9)

This application relates to a novel group of distilbazoles derivatives having anthelmintic activity, especially against

2

in dogs, few clinicians would even consider it for use against human pinworms.

We have found that certain closely related compounds, shown in Formula II, retain this high activity against pinworms while possessed of very low oral toxicities. This effect is presumably due to failure of the compounds II to be absorbed by the digestive system of the host. In this formula, n is an integer having the values 2 and 3, R' is an alkyl group selected from the class consisting of the methyl, ethyl and n -propyl groups, and X^- is the anion of a non-toxic acid.

human pin-worms. This is a continuation-in-part of our preceding application Serial No. 104,798, filed April 24, 1961.

This parasite (*Enterobius vermicularis*) is the most common nematode parasite of the human inhabitants of North America and Europe. It is particularly common among young children and frequently spreads through a family. Since it dwells in the lower intestine, it is difficult to eradicate. At the same time, while it is a nuisance and shocking to the sensibilities of many people, it is not usually dangerous and serious effects upon the host have not been clearly demonstrated.

Because of the relatively innocuous nature of this parasite, clinicians rightly insist that any remedy should itself be non-toxic and otherwise harmless (whereas with more serious infections certain hazards in treatment may be and often have been accepted). One drug in common use against pinworms, piperazine, is both effective and safe. It has, however, the disadvantage that treatment must be continuous over a substantial period of time, for example at least one to two weeks.

In our companion application Serial No. 104,798, filed April 24, 1961, we have disclosed that various distilbazoles such as that shown in Formula I (where X^- is an anion)

are highly effective in eliminating a variety of nematode parasites, including pinworms. This particular compound, unfortunately, is relatively toxic in mice and the therapeutic index is correspondingly low. While its toxicity is not constant from host to host and it may have therapeutic use in certain disorders, e.g. hookworm, especially

This anion does not contribute to the anthelmintic action and its identity is not important as long as it is pharmaceutically acceptable. Iodide, bromide, chloride, toluene sulfonate, and ethyl sulfate, for example, are convenient anions and essentially equivalent values for X^- .

Accordingly, the invention comprises a novel group of distilazole compounds of the preceding formula and the administration of these compounds in the treatment of nematode infestations, particularly human pin-worms.

In Table I are shown the result of tests with illustrative compounds of this invention and of three close relatives, first in regard to toxicity (LD_{50}) in mice and secondly in eliminating the pin-worm of mice, *Syphacia obvelata*. (This parasite has been found in past experience to be of particular value as vectors which indicate drugs useful against the human pin-worm.) It will be seen that the first three compounds of the table, having dimethylamino or diethylamino groups on the benzene rings have LD_{50} values of 25–35 mg./kg. while high efficiency against pinworms requires $\frac{1}{3}$ to $\frac{1}{2}$ of that amount.

The six following compounds are active at about the same level, but have an entirely different order of toxicity (LD_{50} being over 1000 mg./kg. in four of the six cases). All of these compounds were administered as iodides wherefore differences in molecular weights were negligible as regards relative toxicity. When the alkyl group R' is lengthened to the butyl stage, the consistent pattern of high efficiency and low toxicity breaks down, i.e. one of these homologues is relatively ineffective and the other considerably more toxic ($LD_{50}=300$ mg./kg.).

These compounds are conveniently prepared by condensation of two mols of *p*-pyrrolidino or *p*-piperidino-benzaldehyde with a quaternary salt of 2,6-lutidine (in the diagram n , R' and X^- have the same values as above).

Since the compounds II are very sparingly soluble in most

solvents the usual metathetical conversions of anions (e.g. that of an iodide to a chloride by treatment with silver chloride) are rather unsatisfactory. It is consequently convenient to have as the anion of the lutidine quaternary salt that anion which is desired in the product. Again, conveniently, the anion may be that introduced by the alkylating agent. Thus if one desires that in II R' should be ethyl and X⁻ iodide, 2,6-lutidine is alkylated with ethyl iodide. If X⁻ should be the ethylsulfate anion, alkylation would be with diethyl sulfate. Similarly, alkylation of 2,6-lutidine with propyl p-toluenesulfonate affords 2,6-dimethyl-1-propylpyridinium tosylate which is then condensed with p-pyrrolidinobenzaldehyde or p-piperidinobenzaldehyde to give 2,6-bis-p-pyrrolidino or piperidino styrylpyridine n-propyl tosylate.

Alternatively, metathetical interconversions are readily accomplished at this stage so that to make a Compound II where X⁻ is chloride, it is easy to convert 2,6-lutidine methiodide to the metho-chloride by warming with methanolic hydrogen chloride.

The compounds II are dark-colored crystals whose surface color ranges from dark red to almost black. They melt with probable decomposition well above 200° and are sparingly soluble in virtually all solvents, the solutions being pinkish or reddish if sufficiently concentrated. In water so little material dissolves that the solvent is not visibly colored. The color is due to an intense but broad absorption band, approximately identical as between the individual compounds. The $\lambda_{\text{max.}}$ is at about 495 m μ ($E_m = 55,000-60,000$) but intense absorption (E_m 40,000 or over) is manifest from about 460-530 m μ .

The melting points being attended by decomposition are somewhat dependent on the rate of heating. Further, the dark color of the compounds renders precise observation of the melting points extremely difficult. The data on melting points of the compounds II must, therefore, be regarded as only approximate. They are of little value for identification and of no value as criteria of purity.

EXAMPLE 1

Preparations

2,6-lutidine ethiodide.—A mixture of 107 g. of 2,6-lutidine and 312 g. of ethyl iodide was refluxed for 24 hours on a steam bath. The product was collected by filtration (1st crop 170 g.), the filtrates were refluxed 24 hours longer (2nd crop 40 g.), and the filtrates again refluxed for 24 hours (3rd crop 15 g.). The total yield was 225 g. (85%). After two recrystallizations from ethanol 185-195 g. (70-75%) of pure product resulted; M. P. 212-214° C.

To prepare the etho-chloride, 10 g. of the ethiodide was dissolved in 200 cc. of methanol and hydrogen chloride gas was run in until 20 g. had been absorbed. The solution was then warmed on the steam bath, most of the solvent being gradually distilled out. One hundred cc. of 10% methanolic hydrogen chloride was then added and the process repeated. Finally the flask was evacuated on the steam bath. The rather hydroscopic residue was the etho-chloride of 2,6-lutidine and was suitable for synthetic purposes without further manipulation.

EXAMPLE 2

N-phenylpyrrolidine.—A mixture of 216 g. of 1,4-dibromobutane, 500 cc. of methanol and 465 g. of aniline was refluxed for 5 hours at 100° C. Methanol was evaporated and 120 g. of sodium hydroxide (as 40-50% aqueous solution) was added to the residue. The organic layer was taken up in ether and dried over anhydrous

potassium carbonate. After removing potassium carbonate and ether the excess aniline was distilled in vacuo and saved, and the product was collected. N-phenylpyrrolidine boiled at 133-134° C. at 19 mm.; the yield was 130 g. (88-90%).

EXAMPLE 3

p-Pyrrolidinobenzaldehyde.—To 32 cc. of dimethylformamide chilled in an ice bath was added 9 cc. (=16 g.) of phosphorus oxychloride over 10 minutes with stirring. To the chilled and stirred mixture 15 g. of N-phenylpyrrolidine was added dropwise during 15-30 minutes. The reaction mixture was heated for 2-2½ hours at 100° C., then was cooled and poured onto 100 g. of ice. The aqueous solution was basified to pH 11 by the addition of about 25 g. of sodium hydroxide (as 40-50% aqueous solution). After standing for ½-1 hour the product was extracted with several portions of ether and the ether extracts were dried over potassium carbonate. After removing potassium carbonate the dried ether solution was concentrated. Upon cooling the product crystallized. The product can be purified by recrystallization from ether in which it is moderately soluble, from hexane in which it is very sparingly soluble, or from mixtures of the two. The yield of pure product was 16 g. (90%); M.P. 85-86° C.

By the same procedure N-phenylpiperidine was converted to p-piperidinobenzaldehyde, M.P., 63-64° C.

EXAMPLE 4

2,6-bis-(p-pyrrolidinostyryl)-1-ethylpyridinium iodide.—A mixture containing 2.6 g. of 2,6-lutidine ethiodide, 100 cc. of methanol, 4.2 g. of p-pyrrolidinobenzaldehyde and 1 cc. of piperidine was refluxed on a steam bath. Insoluble solid precipitated and heavy bumping started in less than an hour. After 2 hours this product was collected (2 g.) and the filtrates were refluxed for 20 hours longer. A second crop of 2.5 g. was obtained and on standing another day or so the filtrates gave a third crop of one g. The total yield was 5.5 g. (90-95%) in three crops, M.P. 282-283° C. The product was nearly insoluble in hot methanol and was purified by washing several times with ether and then digesting one or two times with 10-20 times its weight of hot methanol. Because it is difficult to recrystallize it is desirable that nearly all insoluble impurities (dust, boiling stones, etc.) be removed from the easily purified reactants before the final condensation step and be kept out as much as possible thereafter.

On a larger scale bumping can become a major problem. In such cases a powerful stirrer should be used or the reaction-mixture should be held at 60-65° C. or below the boiling point of methanol.

When the p-pyrrolidinobenzaldehyde is condensed by the same procedure with 2,6-lutidine ethochloride, the product is 2,6-bis-(p-pyrrolidinostyryl) pyridine ethochloride which decomposes above 270° and on gross examination cannot be distinguished from the ethiodide. Different values are obtained on analysis.

By the same procedures p-pyrrolidinobenzaldehyde was condensed with 2,6-lutidine methiodide and 2,6-lutidine-n-propoxide to give 2,6-bis-(p-pyrrolidinostyryl) pyridine methiodide and propoxide. These compounds melted with decomposition at 295-7° and 265-7° respectively. Condensation of the aldehyde with 2,6-lutidinepropyl tosylate afforded 2,6-bis-(p-pyrrolidinostyryl) pyridine propyl tosylate which decomposes around 260°.

Similarly p-piperidinobenzaldehyde was condensed with 2,6-lutidine methiodide, ethiodide and propoxide giving 2,6-bis-(piperidinostyryl) pyridine methiodide, ethiodide and propoxide which melt with decomposition at 222-5°, 242-4° and 228-9° respectively.

TABLE I.—ACTIVITIES AND TOXICITIES OF COMPOUNDS OF THE FORMULA

WRL No.	R ₂ N	R'	LD ₅₀ , mg./kg. (mice)	Effectiveness against <i>Styphacis</i> <i>obvelata</i> in mice		
				Single dose mg./kg.	Percent worms removed	Mice cleared/ Mice dosed

What we claim is:

1. A compound of the formula

wherein n has the values of 2 and 3, R is selected from the class consisting of the methyl, ethyl and n-propyl groups, and X^- is an anion derived from a pharmaceutically acceptable acid.

any acceptable acid.

3. 2,6-bis-(pyrrolidinostyryl)-1-ethylpyridinium iodide.

4. 2,6-bis-(pyrrolidinostyryl) - 1 - propylpyridinium iodide.

5. 2,6-bis-(piperidinostyryl)-1-methylpyridinium iodide.
6. 2,6-bis-(piperidinostyryl)-1-ethylpyridinium iodide.
7. 2,6-bis-(piperidinostyryl)-1-propylpyridinium iodide
